UNITED STATES PATENT OFFICE.

WALTER WALLACE LECK, OF STEELTON, PENNSYLVANIA.

GUIDE FOR ROLLING-MILLS.

1,217,611.

Specification of Letters Patent. Patented Feb. 27, 1917.

Application filed September 26, 1916. Serial No. 122,225.

To all whom it may concern:

Be it known that I, WALTER W. LECK, a citizen of the United States, residing at Steelton, in the county of Dauphin and State of Pennsylvania, have invented certain new and useful Improvements in Guides for Rolling-Mills, of which the following is a specification.

My invention consists of an improvement in guides or manipulator side guards for rolling mills, particularly for ingot or billet rolls, and is designed to provide for positive alinement of the billet with relation to the rolls and feeding rollers, and to obviate the possibility of damage due to interference.

Ordinarily, an ingot or billet is guided to or from the rolls by laterally arranged guide or side guard bars which frequently obstruct or interfere with the ingot by endwise accidental engagement, causing breakage and stoppage of the mill.

In my improved guides this tendency is entirely obviated by the novel construction and mounting of the guides.

In the drawings illustrating the invention:

Figure 1 is a perspective view showing portions of the guides in operative relation to the stand of rolls.

Fig. 2 is a similar enlarged view showing the guides in detail, detached.

The rolls 2, 2, of the mill are mounted in the usual housing 3 at each side of which are usually arranged the series of feed rollers 4, 4, preferably positively driven, for feeding the blank, to and from the rolls, and mounted by their journals in a suitable carrying frame or table 5.

My improved guides 6, 6, in the form of rectangular bars, or of other suitable cross section, are mounted longitudinally along and across the feed rollers at each side of the pathway of the blank, as shown, and rest upon suitable supports closely adjacent to the feed rollers.

The under sides of the guide bars are concaved at intervals, as indicated at 7, for clearance, and each guide is provided with a pair or other suitable number of manipulating arms 8 secured to its under portion and capable of being connected with any convenient manipulating mechanism by cross portions 9, whereby the guide bars

may be moved laterally in either direction, 55 or toward or from each other.

The end portions of the bars 6 are tapered down as indicated at 10 and provided with terminal lips 11 which fit down over one of the feed rollers 4. By this construction the 60 guides are provided with skid portions over which the ingot will ride without interference in the event of accidentally not registering with the pass between the guides, as in case of failure to shift them promptly 65 or accurately, thus preventing any interference and resulting damage. The retaining lips 11 maintain the guides against longitudinal movement, and insure against displacement, while facilitating the lateral 70 shifting.

The guides are preferably provided with the skid portions at each end, so as to prevent interference either with a new hot ingot in its passage toward the rolls, or in its 75 passage from the rolls outwardly in either direction, during rolling.

What I claim is:

1. In combination with reducing rolls, a pair of laterally adjustable guide bars 80 adapted for adjustment with relation to the pass of the rolls each having a downwardly sloping terminal.

2. In combination with reducing rolls, a pair of laterally adjustable guide bars 85 adapted for adjustment with relation to the pass of the rolls each having a downwardly sloping terminal and a retaining lip.

3. In combination with reducing rolls and a series of feed rollers therefor, a pair 90 of laterally adjustable guide bars laid across the feed rollers each having its terminal adjacent the reducing rolls sloped downwardly for clearance of the article being rolled.

4. In combination with reducing rolls and a series of feed rollers therefor, a pair of laterally adjustable guide bars laid across the feed rollers each having its opposite terminals sloped downwardly for clearance of 100 the article being rolled.

5. In combination with reducing rolls and a series of feed rollers therefor, a pair of laterally adjustable guide bars laid across the feed rollers each having its terminal adjacent the reducing rolls sloped downwardly for clearance of the article being rolled and provided with a downwardly extending re-

taining lip engaging over one of the feed rollers.

6. In combination with reducing rolls and a series of feed rollers therefor, a pair of laterally adjustable guide bars laid across the feed rollers each having its terminal adjacent the reducing rolls sloped downwardly for clearance of the article being rolled and

provided on its underside with concave clearance openings for the feed rollers.

In testimony whereof I hereunto affix my signature in the presence of two witnesses.

WALTER WALLACE LECK.
